Patented Oct. 8, 1918.

UNITED STATES PATENT OFFICE.

DANIEL H. PRUTTON, OF CLEVELAND, OHIO.

AIR-PUMP.

1,281,068.

Specification of Letters Patent.

Patented Oct. 8, 1918.

Application filed January 17, 1918. Serial No. 212,286.

To all whom it may concern:

Be it known that I, DANIEL H. PRUTTON, a citizen of the United States, residing at Cleveland, in the county of Cuyahoga and State of Ohio, have invented certain new and useful Improvements in Air-Pumps, of which the following is a specification.

This invention has relation to air compressors, and has for an object to provide an air compressor designed particularly for embodiment in motor vehicles, and particularly motor vehicles of the Ford type with means for operating the compressor by means of the prime mover of the vehicle.

Another object of the invention is to provide an air compressor and operating mechanism therefor, including a commutator cap adapted to be used in place of the commutator cap embodied in motor cars of the Ford type, an air compressor proper mounted upon said timer cap, and an operating mechanism for the compressor designed for direct connection to the shaft within the timer.

A still further object of the invention is to provide an air compressor of the piston and cylinder type operable by means of a rotating shaft, and embodying a timer cap rotatably connected to the compressor, and a clutch mechanism associated with the shaft for direct connection to the timing shaft whereby the compressor may be actuated, the timer cap being shiftable in the usual manner to advance or retard the shock.

In addition to the foregoing my invention comprehends improvements in the details of construction and arrangement of the parts to be hereinafter more fully described and particularly set forth in the appended claims.

In the accompanying drawings in which similar and corresponding parts are designated by the same characters of reference throughout the several views in which they appear:

Figure 1, is a view in front elevation of the casing containing the timing gears, and illustrating the relation thereto of my air compressor.

Fig. 2, is a view in vertical section, with the timing cap partly in section, and partly

in elevation taken on the line 2—2 of the preceding figure, and

Fig. 3, is a detail section taken on the line 3—3 of Fig. 2.

With reference to the drawings, 10 indicates the front plate of the casing containing the timing gears, the structure shown being that embodied in the Ford type of motor vehicle. The timer shaft, which extends centrally through the casing is indicated at 11, and in the present instance the forward end is pointed as at 12 to form a clutch surface for a purpose which will be presently obvious.

Mounted upon the front plate of the casing containing the timing gears is the timing cap 13 adapted for rotation through a partial revolution to advance and retard the spark. The timing mechanism including the commutator and timing cap are well known and hence a detailed description thereof is not necessary for the comprehension of my invention.

For the purposes of my invention, the timer cap 13 is formed with a central opening 14, and the outer surface of the cap is recessed as at 15 around said opening. The outer face of the timer cap is frusto-conical in configuration, and is formed with an annular race-way 16 terminating in a radial annular flange 17. The compressor consists of a circular casing 18 formed of an upper half 19, and a lower half 20, the same being separable and connected together by means of fastenings 21 which penetrate apertures in the flange 22 formed on the meeting edges of said sections. The section 19 of the casing is formed with a cylinder 23 having an extension 24 at its outer end or head end, the same being reduced and threaded as at 25 to receive a sleeve or valve casing 26. The reduced end 25 is formed with a valve seat against which a spherical valve 27 bears, said valve being held in place by means of a coil spring 28 which engages the same and bears against a shoulder formed interiorly of said valve casing. The head of the cylinder is also formed with an opening 29 which is normally closed by means of a flat valve 30 provided interiorly of the cylinder whereby to permit the entrance of air into

the cylinder upon an intake stroke of the piston but to close upon a working stroke. The valve 27 operates in a reverse manner.

A piston 31 operates in the cylinder and is provided upon its outer end with a reduced portion 32 against which a washer or gasket 33 of soft material is placed having the periphery thereof bent around the reduced portion 32 of the piston, the packing being held in place by means of a washer 34 applied thereto and held in place by means of a screw 35 which penetrates said washer, the packing gasket and the piston. The under side of the piston is hollowed out, and a wrist pin 36 is passed transversely therethrough to which the outer end of a connecting rod 37 is connected. The opposite end of the connecting rod is formed with an annular enlargement 38 forming an eccentric cap, formed in disconnectable sections to receive the eccentric disk 39 which is formed integrally with the shaft 40. The shaft 40 passes transversely through the casing of the compressor and is assembled therein before the sections 19 and 20 of the casing are connected together. To prevent longitudinal movement of the shaft, collars, 41 are formed integrally upon the shaft to bear against the faces of the casing.

One end, viz: the outer end of the shaft 40 is formed with a longitudinally extending key-way 42, and said shaft 40 is formed with a longitudinally extending channel passing entirely therethrough to receive a rod 43 which extends therethrough. This rod 43 is provided with a key 44 which normally rests in and operates within the key-way 42 so as to lock the shaft 40 to the rod for rotation in unison, but to permit sliding movement of the rod 43 relative to the shaft in a longitudinal direction. Formed integrally upon the outer face of the casing 18 of the compressor and centrally thereof is an enlargement 45 having a rectangular exterior. The shaft 40 passes through said enlargement, and secured to the end of said enlargement is a spring finger 46 which normally bears against the rod 43. The outer end of the rod 43 is formed with an annular groove 47 in which the spring finger 46 becomes heated at times. To facilitate shifting of the rod 43, the outer end thereof is provided with a knob 48.

The opposite or inner end of the shaft 40 extends into the recess 15 of the timer cap, and the adjacent end of the rod 43 passes beyond said end of the shaft 40 and is threaded for connection to the reduced end 49 of a receptive clutch member 50. Said clutch member 50 is in the nature of an annular block having its outer face formed with an annular recess, the same being lined as at 51 with material designed to afford firm frictional engagement with end 12 of the commutator shaft. The reduced end 49

of the receptive member snugly engages the opening 14 of the timer cap so as to be slidably and rotatably mounted therein and encircling the inner end of the shaft 40 is a coil spring 52 which bears at one end against the bottom of the recess 15, and at its opposite end against a washer 53, the washer in turn bearing against a pin 54 which passes through longitudinally extending slots 55 in the shaft 40, and through an opening in the rod 43 in which rod the pin is secured. The inner side of the compressor casing 18 is formed with an annular enlargement 56, having an annular recess 57 which is designed to receive the flange 17 of the timer cap, and is also formed with an inwardly directed annular flange 58 having an annular ball race-way 59 therein in which spherical bearing members 60 are placed to engage the race-way 16 of the timer cap. In this manner the timer cap is fixed to the compressor casing for rotation relative thereto, to permit adjustment of the timer cap for the purposes of advancing or retarding the spark. In order that the compressor casing may be rigidly held against rotation, I provide an arm indicated at 61, having one end fixedly secured at 62 to the casing containing the timing gears, and its opposite end formed with an enlargement 63 having a squared aperture 64 in which to receive the rectangular enlargement 45 of the compressor casing.

Normally, the coil spring 52 within the recess of the timer cap urges the rod 43 outward and thereby retains the receptive member 50 of the clutch out of engagement with the timer shaft. The timer is thus permitted to rotate without affecting the compressor whatsoever. However, when it is desired to start operation of the compressor it is but necessary to push upon the knob 48 so as to move the rod 43 longitudinally until the clutch member 50 is fixedly engaged against the commutator shaft 11. The clutch members being held in such engagement by the engagement of the spring finger 46 in the groove 47 of the rod. Rotation of the commutator shaft is then transmitted to the receptive clutch member 50, thence through the rod 43, and key 44 to the shaft 40. Rotation of said shaft 40 is converted into reciprocatory movement of the piston 31 by means of the eccentric connection thereby compressing the air within the cylinder which may be conveyed by means of a hose or other means attached to the valve casing 26 to the tire or other device or machine to be supplied with air under pressure. Actuation of the compressor may be stopped by pulling upon the knob 48 so as to disconnect the clutch members.

While I have illustrated and described my invention with some degree of particularity, I realize that in practice various alterations

thereover may be made and I therefore desire to reserve the right and privilege of changing the form of the details of construction, or otherwise altering the arrangement of the correlative parts without departing from the spirit of the invention or the scope of the appended claims.

Having thus described my invention what I claim as new and desire to secure by Letters Patent is:—

1. In a motor vehicle, the combination with the timer shaft and timer cap, of an air compressor mounted upon said cap, and means for operatively connecting the working parts of the compressor to the timer shaft.

2. In a motor vehicle, the combination with the timing shaft and timer cap, of a compressor rotatably mounted on the timer cap, and means for operatively connecting the compressor to the timer shaft.

3. In a motor vehicle, including the timer shaft and timer cap, of a compressor casing, means for rotatably connecting the timer cap to the compressor casing, a compressor mechanism within the casing, and means for operatively connecting said compressor mechanism to the timer shaft.

4. In a motor vehicle, the combination with the timing gear casing, the timer shaft, and timer cap rotatable relative to the casing, of a compressor casing rotatably mounted upon the timer cap, means connecting the compressor casing to the timer casing to prevent rotation of the compressor casing but to permit rotation of the timer cap, a compressor mechanism within the compressor casing, and means for operatively connecting said compressor mechanism to the timer shaft.

5. In a motor vehicle, the combination with the timing gear casing, the timer cap rotatable relative thereto, and the timer shaft, of a compressor casing, means for rotatably connecting the timer cap to the compressor casing, a polygonal enlargement formed on the compressor casing, an arm rigidly connected at one end to the timing gear case and having a polygonal aperture at its other end to receive the polygonal enlargement of the compressor casing, compressor mechanism within the compressor casing, and means for operatively connecting said compressor to the timing shaft.

6. In a motor vehicle, the combination with the timing gear casing, the timing cap and commutator shaft, of an annular extension on said timer cap to form a ball-bearing race-way, an annular radial flange terminating said extension, a compressor casing having an annular extension formed with an annular recess to receive the annular flange, and an annular race-way for juxtaposition with the race-way of the timing cap, ball-bearing members in said race-ways, means

for rigidly connecting the compressor casing to the timer casing, compressor mechanism within the casing, and means for operatively connecting said mechanism to the commutator shaft.

7. In a motor vehicle, the combination with the timing cap and commutator shaft, of a conical terminal formed on said commutator shaft to form a clutch member, a compressor casing mounted on the timer cap, compressor mechanism within the casing, a receptive clutch member for association with the end of the commutator shaft, means operatively connecting said clutch member with the operating mechanism of the compressor, and means for moving the receptive member of the clutch into engagement with the commutator shaft, to transmit motion to the compressor mechanism.

8. An air compressor attachment for motor vehicles, including a timer cap, a compressor casing, mounted thereon, a shaft mounted in the casing, a compressor mechanism operable upon rotation of said shaft, and means for connecting said shaft to the commutator shaft of a motor vehicle to actuate the compressor mechanism.

9. An air compressor attachment for motor vehicles, including a timer cap, a compressor casing mounted thereon, a hollow shaft extending through the compressor casing and timer cap, a compressor mechanism operable by rotation of said shaft, a rod slidably mounted in the shaft, means connecting the shaft to the rod for rotation in unison but to permit sliding movement of the rod, and a clutch member on one end of the rod for engagement against the commutator shaft of the motor vehicle to transmit power to the compressor mechanism.

10. An air compressor attachment for motor vehicles including a timer cap, a compressor casing mounted thereon, a hollow shaft passing through the casing and cap, compressor mechanism operable by rotation of said shaft, a rod passing through the shaft and connected thereto for rotation, said rod being mounted therein for sliding movement, said shaft having longitudinally extending slots, a pin passing through said slots and fixedly secured to the rod, a spring within the timer cap engaging the pin to retain the rod in one position, and a clutch member secured to one end of the rod for engagement with the commutator shaft of the motor vehicle when the rod is moved against said spring to transmit power to the shaft.

11. An air compressor attachment for motor vehicles, including a timer cap having a central opening and a recess formed around said opening, a compressor casing mounted on the cap, a hollow shaft passing through the casing, and the opening of the timer cap, said shaft having longitudinally extending recesses, located within the recess of the

timing cap, a rod passing through the shaft for sliding movement, means connecting the shaft to the rod for rotation in unison, a pin rigidly fixed to the rod and having its terminals extending through the slots of the shaft, a washer surrounding the shaft and engaging the pin, a coil spring mounted within the recess of the timer cap to engage the washer to retain the rod in one position, 10 a knob on one end of the rod to move the same against tension of the spring, a clutch member mounted upon the other end of the

rod having a recess to receive the commutator shaft of the motor vehicle, a compressor mechanism operable by rotation of 15 the shaft, and means for releasably retaining the rod in an inward position.

In testimony whereof I affix my signature in presence of two witnesses.

DANIEL H. PRUTTON.
